Specification for Design.

Patented July 20, 1915.

Application filed January 4, 1915. Serial No. 537. Term of patent 3½ years.

To all whom it may concern:

Be it known that I, FRANZ A. FULLER, a citizen of the United States, residing in the city of Newark, county of Essex, and State of New Jersey, have invented a new, original, and ornamental Design for a Bag-Frame Member; and I do hereby declare the following to be a full, clear, and exact description of the invention, reference being had to the accompanying drawings, and to letters of reference thereon, which form a part of this specification.

Figure 1 represents a front elevation of a bag frame embodying my new design; and Fig. 2 represents a plan view of the same.

As shown in the drawings, my design consists in an ornamental bag frame member having a central portion of greater depth than the other portion of the frame member.

I claim:

The ornamental design for a bag frame member as shown and described.

FRANZ A. FULLER.
